CLAIM

I claim the ornamental design for a roof vent with a circular integrated fan, as shown and described.

DESCRIPTION

FIG. 1 is a top perspective view of a roof vent with a circular integrated fan;

FIG. 2 is a top view of the vent of FIG. 1;

FIG. 3 is a bottom view of the vent of FIG. 1, having an upper and lower screen;

FIG. 4 is a bottom view of a second embodiment vent of FIG. 3, having an upper screen only;

FIG. 5 is a bottom view of a third embodiment of the vent of FIG. 3, having no screens;

FIG. 6 is a front view of the vent of FIG. 1;

FIG. 7 is a rear view of the vent of FIG. 1;

FIG. 8 is a right side view of the vent of FIG. 1; and,

FIG. 9 is a left side view of the vent of FIG. 1.

The dashed broken lines in the figures represent features of the roof vent with a circular integrated fan that form no part of the claimed design. In the drawings, the dot-dash broken lines define the bounds of the claimed design and form no part thereof.
